DESIGN FOR A TARGET GAME BOARD

Eldridge B. Taylor, Cleveland, Ohio

Application March 11, 1944, Serial No. 112,876

Term of patent 7 years

(Cl. D34—5)

To all whom it may concern:

Be it known that I, Eldridge B. Taylor, a citizen of the United States, residing at Cleveland, in the county of Cuyahoga, and State of Ohio, have invented a new, original, and ornamental Design for a Target Game Board, of which the following is a specification, reference being had to the accompanying drawing, forming part thereof, wherein:

The figure of the drawing is a plan view of the target game board showing my new design, the board being of conventional thickness.

I claim:

The ornamental design for a target game board, substantially as shown and described.

ELDRIDGE B. TAYLOR,
